Primary Examiner — Thomas Johannes*Assistant Examiner* — Shawn T Gingrich(74) *Attorney, Agent, or Firm* — Shlesinger, Arkwright & Garvey LLP(57) **CLAIM**

The ornamental design for a swivel joint, as shown and described.

DESCRIPTION

FIG. 1 is a top perspective view of a swivel joint, showing the inventor's new design;

FIG. 2 is a side view thereof, the opposite view being a mirror image;

FIG. 3 is a top view of the inventor's swivel joint of FIG. 1; and,

FIG. 4 is a front view thereof.

Any surface not shown forms no part of the claimed design. The broken line portion of the figure drawings is included to show portions of the article which form no part of the claimed design.

1 Claim, 2 Drawing Sheets(56)
